NONMETALLIC PLASTIC GARMENT SUPPORT

Lucy M. Hachovina, San Diego, Calif.

Application March 14, 1946, Serial No. 654,298

5 Claims (Cl. 223-91)

1

My invention relates to a nonmetallic plastic garment support mounted with the shoulder arms integral with one of the horizontal bars which forms a clamp for supporting garments below the shoulder arms of the hanger.

It is a feature to provide a nonmetallic plastic garment support wherein one of the clamping bars for the skirt or pants clamp is integral with the shoulder arms and the other clamping bar is hinged to the first bar on one end and is held by a plastic nonmetallic slideable locking key on its free end to lock the same with the back clamping bar, thus holding the garment by the clamping bars below the shoulder arms.

A further feature resides in providing a nonmetallic plastic garment support wherein a pivoted hook is connected on one end at the apex at the joining of the arms of the hanger and which hook is adapted to turn freely on its shank at the top of the shoulder arms.

I also provide a plastic hanger wherein a slideable locking key made of plastic is formed with a U-shaped end and is adapted to be provided with longitudinal shoulders which engage in complementary recesses formed in the back bar and in the free end of the front bar which act to clamp a garment between the same. The locking key is adapted to be embedded in the body of the clamping bars so when the key is in locked position it is flush with the outside surface of the bars. The edges of my garment support are rounded and smooth to prevent any undue wear on the garment supported by the hanger and provide a smooth light-weight hanger which may be made in any desired color to make the same very attractive.

These features together with other details and objects will be more fully and clearly hereinafter set forth:

In the drawings forming part of the specification:

Figure 1 is a perspective view of my garment support.

Figure 2 is a section on the line 2-2 of Figure 1.

Figure 3 is an enlarged section on the line 3-3 of Figure 2.

Figure 4 is a back view showing a detail of the garment support which shows the slideable key in closed position.

Figure 5 is an enlarged perspective view of the slideable locking key removed from the hanger A.

The garment hanger A is designed to be made of plastic or nonmetallic material and is formed

2

with the shoulder arms 10 which connect at the apex 11.

5 A metallic hook 12 has its shank 13 pivotally connected and extending through the enlarged portion 14 which connects the top ends of the arms 10. The lower end of the shank 13 is formed with a head portion 14 to pivot the hook 12 to the garment hanger A.

10 The arms 10 are formed integral with a horizontally extending back bar portion 16 which connects the lower ends of the arms, thus the horizontal back bar 16 connects the arms 10 and forms a straight bridge between the members.

15 The front bar 17 is formed similarly to the back bar 16 and is pivotally connected at 18 on one end to the back bar 16. The front end of the bar 17 is formed with an undercut slot 19 which is adapted to receive the short end 20 of the U-shaped locking key 21 which is formed with a long end 22 on the back which is adapted to slide and be anchored in the undercut slot 23 formed in the back bar 16.

20 The U-shaped slideable locking key 21 is formed with longitudinally extending rib portions 24 on the short arm 20 and the long arm 22. These ribs fit into the undercut recess formed in the respective slots 19 and 23 to hold the U-shaped locking member 21 in a manner to rigidly connect the front end of the bar 17 to the back bar 16. It will also be apparent that the sliding locking key 21 will keep the free end of the bar 17 in line with the back bar 16.

25 Thus I provide a hanger A made of plastic or nonmetallic material wherein the shoulder arms and the back clamp bar are formed integral. The back bar 16 has the slot 23 formed in one end adjacent the free end of the arm 17 and the free end of the arm 17 has a slot 19 formed therein to receive the short end or like of the slideable 30 U-shaped clamping member 21. The clamping bar 17 is also formed of plastic or nonmetallic material and is hingedly connected at 18 to the bar 16.

35 Thus I provide a garment hanger A with the clamping bars 16 and 17 between which a skirt or pants legs may be engaged to hold the same while a jacket or coat may be hung on the shoulder arms 10. The U-shaped slideable locking key keeps the clamping members 16 and 17 closed and locked together to hold the garment between the bars 16 and 17.

40 The key 21 for locking the clamping bars 16 and 17 is formed with a knob 25 which permits the key 21 to be slid into open position as 45 illustrated in dotted outline in Figure 1.

My hanger A is adapted to be made out of moulded plastic in any color and is simple in construction. The clamping bars 16 and 17 are adapted to hold the garments like a skirt or a pair of pants while the shoulder arms 10 will support a jacket or coat.

I claim:

1. A garment hanger including, shoulder arms, a horizontal bar integrally connecting the lower ends of said arms, a complementary bar hinged to said first bar and adapted to form a skirt and pants holder and a U shaped clamping member slidably anchored in the ends of said front and back bars to hold the same in line and clamped together.

2. A nonmetallic garment hanger including a bar with shoulder members joined at their apex, enlarged portions at said apex for receiving the shank of a hook, a hook for supporting said hanger and extending through said enlarged head portion, a horizontal clamping back bar member integral with the lower ends of said shoulder members, a front clamping bar member pivoted on one end to said back bar member, a shoulder recess formed in the free end of said front bar member and in the complementary end of said back bar member, and a slidable key member having rib portions formed on a portion of the outer edge thereof and adapted to be received by said recess for locking said front and back bar members together and adapted to hold the same in line to provide a skirt and garment clamp support along the base of said hanger.

3. A garment hanger including, a pair of upwardly convergent shoulder arms joined at an enlarged portion, a hook pivotally connected to said enlarged portion, a horizontal bar member connecting the lower ends of said shoulder arms, a complementary front bar member pivoted on one end to said back bar member, a slidable key having shoulders formed on a portion thereof, re-

cesses formed in the free ends of said back and front bar members adapted to receive said slideable key and lock said back and front bar members together and hold the same in line, and a knob 5 formed on said key projecting in a manner to provide a finger engaging means whereby said key can be operated to move the same into unlocked and locked position for said bars.

10 4. A garment hanger formed of nonmetallic material including, shoulder portions and a clamping means for garments at the base of said hanger, said clamping means including a pair of horizontal clamping bars hinged together, undercut slots formed in the free ends of said bars, said bars having their opposed clamping surfaces in a vertical position and a U shaped slideable key having shoulders adapted to be received by said undercut slots in the ends of said clamping bars and having a projecting knob for engagement to operate said key.

15 5. A garment hanger including shoulder arms joined at their top ends, a back bar connecting the lower ends of said shoulder arms, a front bar hinged to one end of said back bar to form a clamp, a U shaped slideable locking key, and means for allowing said locking key to slidably fit into the free end of said front bar and the end of said back bar to lock said bars in a predetermined position.
